UNITED STATES PATENT OFFICE

155,613

DESIGN FOR A FOUNTAIN PEN

David Kahn, Englewood, N. J., assignor to David Kahn Inc., North Bergen Township, N. J., a corporation of New Jersey

Application May 3, 1949, Serial No. 2,415

Term of patent 14 years

(Cl. D74—17)

To all whom it may concern:

Be it known that I, David Kahn, a citizen of the United States, residing at Englewood, in the county of Bergen and State of New Jersey, have invented a new, original, and ornamental Design for a Fountain Pen, of which the following is a specification, reference being had to the accompanying drawing, forming a part thereof, wherein:

Fig. 1 is a front elevational view of the fountain pen embodying my new design;

Fig. 2 is a side elevational view of the fountain pen;

Fig. 3 is a top plan view of the fountain pen; and

Fig. 4 is a fragmentary enlarged elevational view of a portion of the cap and a portion of the barrel.

The essential features of my design for a fountain pen reside in the parts shown in full lines.

I claim:

The ornamental design for a fountain pen, substantially as shown and described.

DAVID KAHN.
